UNITED STATES PATENT OFFICE.

EUGENE T. TURNER, OF ROCK ISLAND, ILLINOIS, ASSIGNOR TO ARTISTA PIANO
PLAYER CO., OF MILAN, ILLINOIS, A CORPORATION OF ILLINOIS.

SUPPORT FOR MUSICAL-INSTRUMENT MOTORS.

1,125,216.

Specification of Letters Patent.

Patented Jan. 19, 1915.

Application filed March 20, 1908. Serial No. 422,276.

To all whom it may concern:

Be it known that I, EUGENE T. TURNER, a citizen of the United States, residing at Rock Island, in the county of Rock Island and State of Illinois, have invented certain new and useful Improvements in Supports for Musical-Instrument Motors, of which the following is a specification.

This invention relates to improvements 10 in motor supports, particularly adapted for use with playing attachments for musical instruments of the type employing an electric spring, air or other motor for driving the operating mechanisms, and the primary 15 object of the invention is to provide an improved flexible, non-resonant support for the motor, whereby the casing of the instrument will be relieved of all vibration of the motor and the humming and buzzing of 20 the motor will be overcome.

A further object is to provide an improved, simple, durable and efficient support for suspending the motor within the casing and by means of which the motor may be 25 readily placed and secured in position and may as readily be removed therefrom.

To the attainment of these ends and the accomplishment of other new and useful objects, as will appear, the invention consists in the features of novelty in the construction, combination and arrangement of the several parts hereinafter more fully described and claimed and shown in the accompanying drawings illustrating the embodiment of the invention, and in which—

Figure 1 is an elevation partly in section of an improved support of this character constructed in accordance with the principles of this invention. Fig. 2 is a front 40 elevation of the improved support. Fig. 3 is a view similar to Fig. 1 of a modified form of the invention. Fig. 4 is a plan view of the support shown in Fig. 3.

Referring more particularly to the drawings and in the exemplification of the invention shown in Fig. 1, the numeral 10 designates a member constructed of any suitable material, such as wood or the like, and 11 designates a flexible, non-resonant 50 member which may be constructed of any suitable material, such as leather or the like, and is secured by one extremity to the member 10 by means of suitable fastening devices 12, such as screws or the like. The 55 member 11 is of a suitable length to extend

beyond and depend from the member 10 and to the free extremity thereof is secured the base 13 of the motor 14, whereby the motor will be suspended by the member 11. The motor is adjustably connected in any 60 manner to the base 13 such as by means of an adjusting screw 13^a engaging ears or projections 13^b on the base, and projections 13^c on the motor. The fastening devices 15 pass through the flexible member 11 and 65 through one extremity of the base 13 so that when the support is secured to the casing 16 of the instrument, the motor will be suspended by the non-resonant member 11 and the member 10 is of a suitable thickness to 70 hold the member 11 and the motor base 13 spaced from the casing 16. The member 10 may be removably secured in position in any desired or suitable manner, preferably 75 by means of fastening screws or bolts 17 which pass through the member and into the casing 16.

A supporting rod or member 18 is secured by one extremity to the motor frame 19 preferably by means of the screw or bolt 20, 80 which passes through an eye 21 in one extremity of the rod 18 and which bolt serves to fasten the plate 22 to the motor frame. The bar or rod 18 is of any desired or suitable length and the free extremity thereof is preferably bent to form a hook 22^a, which hook is covered by a suitable non-resonant material 23, such as a rubber sleeve or the like to deaden the noise caused by the vibration of two metallic parts on each other. 85 This hook-shaped end is adapted to engage a suitable eye 24 which is secured into another portion 25 of the casing of the instrument, so that the rod or bar 18 will cooperate with the flexible support 11 for 90 holding the motor in position within the casing. When it is desired to remove the motor, the supports may be readily detached and when it is desired to replace the motor in the casing they may as readily be 95 attached to the casing.

In the modification of the invention shown in Figs. 3 and 4 of the drawings, the support for the non-resonant member 11^a is in the form of a hollow frame comprising 100 spaced side and end members 26, 27, across which the non-resonant member 11^a extends and is secured by its extremities by means of the fastening devices 12 to two of the opposite members of the frame, preferably 105 110

the end members 27 and the non-resonant member is of a width somewhat less than the width of the opening in the frame so that the body portion of the member 11^a is held out of engagement with the frame work. Secured to one of the end members 27 are spaced eye-bolts 28 which are adapted to engage suitable spaced hooks 29, which latter are secured to the casing 16. The 10 other member 27 of the supporting frame is preferably provided with an opening 30 so that when the supporting frame 26 is held in position within the casing of the instrument by means of the eye-bolts 28 and 15 the hooks 29, the frame may be held against displacement by means of a suitable fastening screw or bolt 31, which passes through the opening 30 and into the casing 16. The base 13 of the motor 14 is secured to the 20 non-resonant member 11^a by means of the fastening devices 15 in a manner similar to that shown in Fig. 1 of the drawing and the supporting frame for the non-resonant member is of such a size that the motor base 25 13 will be supported and suspended entirely by the non-resonant member 11^a and held out of engagement with the frame work.

With this improved construction of non-resonant support, it will be apparent that 30 all vibrations of the motor will be taken up by the flexible support 11—11^a and as that is supported out of engagement with the frame and the casing, all humming or buzzing 35 of the motor which is present when motors rest upon a solid base will be overcome, this improved construction at the same time permitting a slight vibratory movement of the motor.

40 In order that the invention might be fully understood by those skilled in the art, the details of the foregoing embodiment thereof have been thus specifically described but

45 What I claim as new and desire to secure by Letters Patent is—

1. A non-resonant support for motors for musical instruments, consisting of a supporting member adapted to be connected with the instrument casing, and a flexible 50 non-resonant member secured to said supporting member with a portion thereof out of engagement with said supporting member, and a motor secured directly to and suspended by said member out of engagement 55 with the supporting member and free to transmit lateral vibrations to said flexible member.

2. In a device of the class described, a 60 supporting member, a flexible non-resonant element secured to said supporting member with a portion thereof out of engagement with the supporting member, a motor secured directly to said element at one side thereof and out of engagement with the supporting member, and an independent non-

resonant suspension device connected with the motor, said device comprising a rod connected at one end to the motor and having a hook at the other end, and a non-resonant sleeve covering the hook. 70

3. In a device of the class described, a supporting element, a leather member secured to the element, a base supported by the leather member out of contact with the element, the base being formed with threaded lugs, an electric motor having threaded lugs, and a screw adapted to engage in the lugs to hold the motor adjustably in position. 75

4. A support for a motor comprising a 80 sheet of flexible non-resonant material, means for supporting said sheet, and means for attaching the motor to said sheet and suspending the motor free to impart its lateral vibrations to said sheet. 85

5. A support for a motor comprising a 90 sheet of flexible non-resonant material, means for supporting said material in a flattened position, and means for attaching the motor to said sheet and against one of the flattened surfaces thereof. 90

6. A support for a motor comprising a 95 sheet of flexible non-resonant material, means for supporting said sheet in a substantially vertical plane, and means for attaching the motor to one of the surfaces thereof whereby lateral vibration of the motor will be absorbed by the sheet. 95

7. A support for a motor comprising a 100 sheet of flexible non-resonant material, means for supporting said sheet so that a portion thereof will be out of contact with said supporting means, and means for attaching the motor to said portion and freely suspending the motor to transmit its vibrations to said sheet. 105

8. In a device of the class described, a supporting element, a sheet of flexible non-resonant material attached to said supporting element so that a portion thereof is free 110 from said supporting element, and means for attaching a motor to one surface of the free portion of said sheet.

9. In a device of the class described, a supporting member, a flexible non-resonant 115 suspension member attached to said supporting member so that a portion thereof is free from said supporting member, means for attaching a motor to the free portion of said suspension member, and a supplemental support for said motor. 120

10. In a device of the class described, a supporting member, a sheet of flexible non-resonant material attached to said supporting member so that a portion thereof is free 125 from said supporting member, means for attaching the motor to the free portion of said sheet, and a supplemental support for said motor.

11. In a device of the class described, a 130

supporting member, a sheet of flexible non-resonant material attached near one edge thereof to said supporting member, and suspended therefrom so that a portion of said sheet is free from said supporting member, means for attaching a motor to the free portion of said sheet, and a supplemental support for said motor.

In testimony whereof I have signed my name to this specification, in the presence 10 of two subscribing witnesses, on this seventh day of March A. D. 1908.

EUGENE T. TURNER.
